UNITED STATES PATENT OFFICE.

CHARLES L. RIDGWAY, OF BOSTON, MASSACHUSETTS, ASSIGNOR TO THE RIDGWAY FURNACE AND STOVE COMPANY, OF NASHUA, NEW HAMPSHIRE.

HEATING STOVE OR FURNACE.

SPECIFICATION forming part of Letters Patent No. 391,426, dated October 23, 1888.

Application filed July 27, 1885. Serial No. 172,751. (No model.)

To all whom it may concern:

Be it known that I, CHARLES L. RIDGWAY, of Boston, in the county of Suffolk and State of Massachusetts, a citizen of the United States, 5 have invented a new and useful Improvement in Heating Stoves or Furnaces, of which the following is a full, clear, and exact description, reference being had to the accompanying drawings, forming a part of this specification, 10 in explaining its nature.

The invention is an improvement upon that described in United States Patent No. 281,795, issued to me on the 24th day of July, 1883; and it consists in various details of construction, 15 all of which will hereinafter be fully described.

Referring to the drawings, Figure 1 represents a vertical central section of a furnace having the features of my invention. Fig. 2 is a view in horizontal section upon the line $x-x$ of Fig. 1, a portion of the upper part of the fire-pot wall being removed to show a plan of the parts below. Fig. 3 is a view in elevation of a portion of the base of the furnace and of the fire-pot wall, a portion thereof being removed the better to show the construction. 20 Figs. 4 and 5 are enlarged detail views of the fire-pot wall. Fig. 6 is a horizontal section upon the line $y-y$ of Fig. 1 and a plan of the parts below such line.

30 Referring further to the drawings, A represents the ash-pit, and a the entrance or passage thereto, the opening of which is closed by the door a' .

B is the fire-pot; b , the fire-pot wall; b' , a 35 chamber about the fire-pot wall, which is a downward extension of the combustion-chamber C; and b^2 is an opening or passage to the chamber b' , which is closed by the door b^3 .

b^4 is the casing or radiator-shell which 40 forms the chamber b' and the combustion-chamber C.

D is the grate.

c is the entrance or passage to the combustion-chamber, and c' the door for closing the 45 same.

The fire-pot is preferably made of independent sections b^5 , having the vertical bars b^6 and the vertical spaces b^7 between them, the upper horizontal sections, b^8 , and the lower hori-

zontal sections, b^9 . These vertical fire-pot sections b^5 are similar to those described in application Serial No. 172,750, filed by me in the United States Patent Office simultaneously with this application, in that they are placed edge to edge, and in that they are united at 55 the top by a flanged covering-plate, as E, and in that they receive at the bottom a ring-piece, E', which fits within the lower extremity of the sections. In this case, however, the flanged covering-plate is unprovided with 60 exterior horizontal arms, and the fire-pot wall, instead of being suspended by such arms upon brackets or projections from the wall of the combustion-chamber, as described in the application referred to, is supported by the plate 65 e , which is fastened to the wall e' of the ash-pit A and extends inwardly therefrom horizontally, the lower edges of the fire-pot sections b^5 resting thereon, and the fire-pot wall being therefore stationary. The plate e supports, 70 also, the balls f , upon which is mounted the movable plate F, having upon its bottom surface the downwardly-extending teeth f' , with which the pawl d , which is pivoted upon the operating arm or shank d' of the grate, is 75 adapted to engage.

The grate-shank d' extends horizontally from the edge of the grate into the entrance or passage a to the ash-pit, and it rests upon the cross-bar or stirrup-like support d^2 , which is 80 suspended from the frame of the furnace by the depending arms d^3 . From the wall of the ash-pit A an arm, d^5 , is extended horizontally outward to a point which is central to the fire-pot wall and its ring E, and the grate D is 85 provided with a short central bar or web, d^6 , which, when the grate is in place, is received between two oppositely-placed lugs, d^6 d^6 , which project upwardly from the upper surface of the bar, the coincident vertical faces of 90 such lugs being beveled or cut away in a vertical plane to permit reciprocation of the grate, and also to enable the operator to discharge the contents of the grate into the ash-pit as occasion may require, such operation 95 being readily effected by slightly turning the shank of the grate in a vertical plane and downward from left to right.

The pawl d is weighted, so that its upper extremity may be at all times in engagement with the teeth f' , and it therefore follows that upon movement of the shank horizontally to oscillate the grate the plate is caused to revolve. It is necessary to provide this movement, in order that ashes, soot, and other refuse falling from the fire-pot may be moved to a point from which they may be discharged into the ash-pit, and this I prefer to do by means of a scraper or deflector, S , which is arranged to project into the space or passage b^2 at a point opposite the front opening to the chamber b' and immediately above the plate F , and at such an angle as to discharge the ashes and other refuse therefrom as the plate is removed into or through the opening G into the ash-pit. This opening is adapted to be closed by the sliding plate g .

20 The volatile products of combustion may pass directly from the combustion chamber through the passage h to the horizontal pipe h' , which connects with the uptake; or, if it is desired to obtain a larger radiating surface, 25 the damper h^2 in the passage h' may be closed, and the products of combustion will then be caused to pass through the pipe or passage h^3 about the furnace on either side to the passage h^4 at the front of the furnace, which connects the upper pipe, h^5 , or the two sections thereof, with the lower sections or passages, h^6 , which extend about the furnace and open at h^6 into the passage h' .

30 M is the air-heating space or hot-air chamber of the furnace, and m are openings in the casing to receive the heat-conducting pipes m' .

The section N of the furnace, which comprises the inclined plane n , forming the lower surface of the passage to the combustion chamber, and the section n' , forming a portion of the front of the furnace, is removable, and the inner section, n^2 , forms, when in place, a part of the coal-guard n^3 . The plate is made inclined, so that the fuel will not lodge thereon, but will fall through its own gravity into the fire-pot. By making the section removable and of such construction that a portion of it shall act as a coal-guard, the passages to the encircling chamber b' and to the combus-

tion-chamber are upon its withdrawal converted into one and access to the interior of the furnace is more readily effected.

Although I have herein described the system of direct and indirect draft-flues which constitute the radiator of the furnace, it will be understood that I do not herein make claim of novelty therefor, the same being embraced in application Serial No. 193,580, filed by me in the United States Patent Office on the 1st day of March, 1886. It will also be understood that I do not herein broadly claim either a revolute plate at the base of a fire-pot wall or a fire-pot the wall of which is composed of vertical sections, such constructions being shown in my patent, No. 281,795, already referred to.

Having described my invention, I claim--

1. The combination, in a heating stove or furnace, of a stationary fire-pot wall, b , supported above the ash-pit, the non-revolute plate D , suitably held and adapted to be oscillated, and the imperforate movable ash-carrying plate F , substantially as described.

2. In a stove or furnace, the combination of the wall b^4 , surrounding the fire-pot and forming the chamber b' , in connection therewith, the closed chamber b' , extending from top to bottom of the fire-pot, the stationary fire-pot wall b , and the imperforate movable plate F , substantially as described.

3. The combination of the ash-pit wall, the inwardly-projecting imperforate plate e , secured to such ash-pit wall, the isolated fire-pot wall resting upon the plate e , and the chamber b' between the fire-pot wall and the downward continuation of the wall of the combustion-chamber and closed at top and bottom, as described.

4. The combination of the ash-pit wall, the imperforate inwardly-projecting plate e , secured to such ash-pit wall, the isolated non-revolute fire-pot wall, the revolute imperforate ash-carrying plate F , and the scraper or deflector S , substantially as and for the purposes specified.

CHARLES L. RIDGWAY.
